UNITED STATES PATENT OFFICE.

THOMAS L. SOURS AND HOMER F. FOX, OF LURAY, VIRGINIA.

VEHICLE-WHEEL.

No. 806,203.

Specification of Letters Patent.

Patented Dec. 5, 1905.

Application filed December 27, 1904. Serial No. 238,458.

To all whom it may concern:

Be it known that we, THOMAS L. SOURS and HOMER F. FOX, citizens of the United States, residing at Luray, in the county of Page and State of Virginia, have invented certain new and useful Improvements in Vehicle-Wheels, of which the following is a specification.

Our invention relates to vehicle-wheels, and especially to that class of vehicle-wheels known as "spring-wheels."

The object of our invention is to provide a wheel wherein the hub is supported by the elongating strain of the spoke, in which is interposed an incased spring.

15 A further object of our invention is to provide a vehicle-wheel wherein the hub is supported by the elongating strain of the spoke and wherein a spring is interposed in such manner that the elongation of the spoke produces a compression of the spring.

20 It is well known that in all mechanical constructions where the action of a spring is required and wherein it is convenient to place a coil-spring it is always considered highly desirable to so dispose the spring that the pressure exerted will produce a compression of the coils, for the reason that a more equal spring-pressure is thus secured and the spring does not so readily become weakened.

25 30 It is therefore the principal object of our invention to so dispose a coil-spring in a spoke that the elongation of the spoke produces a compression rather than an elongation of the spring.

35 40 With these and other objects in view the present invention consists in the combination and arrangement of parts, as will be herein-after more fully described, shown in the accompanying drawings, and particularly pointed out in the appended claim, it being understood that changes in the form, proportion, size, and minor details may be made within the scope of the claim without departing from the spirit or sacrificing any of the advantages of the invention.

45 In the drawings, Figure 1 is a fragmentary view of a wheel in side elevation, showing several spokes embodying our invention. Fig. 2 is a vertical sectional view in detail of our 50 improved spring for a vehicle-wheel, taken on a line parallel with the axis of the hub. Fig. 3 is a vertical sectional view in detail, taken at right angles to the view shown at Fig. 2 and

on a line transverse to the axis of the hub. Fig. 4 is a transverse sectional view in detail, 55 taken on line 4-4 of Fig. 3.

Like characters of reference designate corresponding parts throughout the several views.

In its preferred embodiment our improved 60 vehicle-wheel consists of a hub 1 of any approved construction forming a center for and encircled by the rim 2. The hub 1 is supported by the spokes 3 from the uppermost point of the rim 2 and by an elongating strain 65 upon the said spoke. A casing 4, provided with a follower 5 and inclosing a spring 6, is interposed in said spoke 3 by means of a staple 7, secured to the hub and passing slidably through the follower 5. The staple 7 also 70 passes longitudinally throughout the casing 4 and is rigidly secured to the upper end of the said casing. A second staple 7 passes slidably through the upper end of the casing 4 and longitudinally through the length of the said casing 75 and is rigidly secured to the follower 5. The spoke 3 is connected with the staple 7 in any approved manner, as by the hook 8.

The operation of our improved vehicle-wheel is as follows: With the parts disposed 80 as shown in the fragmentary view, Fig. 1, the hub 1 is supported from the rim 2 by the spoke 3 and against the expanding pressure of the spring 6. The spring 6 exerts a pressure 85 upon the follower 5, tending to draw the staple 7 farther within the casing 4 and to shorten the spoke, and a pressure upon the hub 1 causes the staple 7 to draw the follower 5 within the casing 4 and against the tension of the spring 6. It is to be observed that the upper end of 90 the casing 4 is closed and that the follower 5 is disposed within the lower end, so that dirt falling from the tire or the rim 2 will not enter the casing 4 and obstruct the proper operation of the follower 5 and the spring 6. 95

Having thus described our invention, what we claim as novel, and desire to secure by Letters Patent, is—

In a vehicle-wheel a spoke provided with a spring interposed therein, a casing disposed 100 about the said spring, said casing having a solid end provided with a plurality of openings therein, a follower disposed within the casing and provided with a plurality of openings, a staple slidably mounted within a pair 105 of openings in the end of the casing and rig-

idly secured to the follower and a second staple, secured at an approximate right angle to the first-mentioned staple, slidably mounted within a pair of openings in the follower and rigidly secured to the end of the casing, said staples and spring constituting a portion of the said spoke.

In testimony whereof we affix our signatures in presence of two witnesses.

THOMAS L. SOURS.
HOMER F. FOX.
